EDWARD N. WINSLOW, OF SHAKER HEIGHTS, OHIO.

SIGNAL MECHANISM.

Application filed April 5, 1927. Serial No. 181,253.

The present invention, relating, as indicated, to signal mechanism is more particularly directed to an improved signal for controlling traffic and for use at street intersections. The present signal is intended to provide an extremely simple and easily operated visual signal and to replace the various types of signals involving the use of banks of colored lights which are now in such general use at street intersections for controlling traffic, and most of which operate by successively connecting into an electrical conduit separate red, yellow and green lights, necessitating a bank of three lights directed along each of the intersecting streets. The present invention is designed to afford the same general operation and method of control but consists of an extremely simple mechanism which requires no multiplicity of lights and can be easily and conveniently installed and operated.

To the accomplishment of the foregoing and related ends, said invention, then, consists of the means hereinafter fully described and particularly pointed out in the claims; the annexed drawing and the following description setting forth in detail certain mechanism embodying the invention, such disclosed means constituting, however, but one of various mechanical forms in which the principle of the invention may be used.

In said annexed drawings:—

Fig. 1 is a view in perspective of my improved mechanism; Fig. 2 is a view similar to the operating part of the device; Fig. 3 is a section on the line 3—3, Fig. 2; Fig. 4 is a plan view with the cover of one form of casing; Fig. 5 is a similar view showing a modification of the construction of Fig. 4; Fig. 6 is a view similar to Figs. 4 and 5, but showing still another modification; Fig. 7 is a plan view with the cover removed of a casing similar to that of Fig. 1, but provided interiorly with an operating element giving four signals for each of the windows or openings in the casing; Fig. 8 is a view in perspective of the interior operating element of Fig. 7; Fig. 9 is a similar view taken from another angle of the same element; and Fig. 10 is a diagrammatic view illustrating one use of my invention at street intersections.

Referring now to Figs. 1, 2 and 3 there is shown a casing 1 in the form of a hollow cube which is intended to be suspended or supported at a street intersection or other

point where it is desirable to signal with the four lateral faces of the cube facing the intersecting streets. While I have described and shown a cube it will be understood that the casing may be in the general form of a sphere with two sets of opposed parallel faces or walls, and that the form of the remainder of the casing, that is the portion which connects these sets of opposed walls, is immaterial. For convenience, however, I shall refer to a casing having such characteristics as a cube. Each of these lateral faces of the cube is provided with an opening 2 in which may be mounted a transparent plate or window, or lens 3, which may be covered by means of a projecting hood or visor 4. On the upper part of the casing there is an extension 5 intended to house the operating mechanism; which will presently be described.

Mounted within the cubical casing 1 is a signaling element in the form of a pivotally mounted cube 10, this element consisting of a box or frame in the form of a cube and having its corners 11 cut off in order to permit it to be rotated freely within the casing without interference with the walls thereof. As in the casing described above the signaling element may be in the general form of a sphere provided that certain sets of faces are arranged around the axis on either side of the element, and the form of the element connecting these faces being in itself immaterial. One half of the signaling elements may be used above which would signal traffic at right angles in two directions. This box-like frame is carried on two shafts 12 and 13 disposed at diagonally opposite corners of the casing and aligned with each other, the shaft 12 being mounted within a bearing or sleeve 14, which is in turn mounted in the corner of the casing and carries thereon a gear 15 which is in engagement with a reciprocable rack bar 16, which, upon longitudinal movement will rotate the gear 15 and with it the entire interior frame about an axis which extends through diagonally opposite corners of this cube. The lower shaft 13 is in the form of a sleeve which is mounted about a tubular element 17 fixed in a boss 18 disposed in one of the lower corners of the outer casing 1.

A thrust bearing 20 is interposed between the end of the boss 18 and the inner or lower end of the sleeve or shaft 13 to support the load of the casing. Mounted on the upper end of the tubular element 21, which is dis-

posed within the boss and passes through a central opening in the sleeve 13, is a source of light in the form of a bulb 22, the electrical connections for which may be carried within 5 a tube 21 to any suitable source of current supply. By means of a bracket the light 22 may be held in vertical position. Either bearing could be eliminated by means of a single supporting bearing at either end designed to support the element and admit source of current. 10 Upon the rotation of the inner signaling member, that is, the cubical frame 10, about the diagonal axis upon which it is mounted, the various faces of this cube are brought 15 into alignment with the windows in the outer casing. This can be most clearly seen by reference to Fig. 2. If the inner cube 10 be rotated about its axis, first the face 25 of the inner cube, which is in alignment with the 20 side 26 of the outer casing, is before the same and parallel thereto, permitting either a word or a signal pictured on the face 25 of the inner cube to be seen through the transparent window in the outer casing, or if a 25 light is mounted in the inner casing, as shown in Fig. 3, this registration permits this light to be seen through the window through the two casings. Upon rotation in a clockwise direction, as viewed from the lower right- 30 hand corner of the outer casing, the face 25 is brought into registration with the next adjacent face 27 of the outer cube, while the surface of the inner cube which was on the bottom in the first position is swung 35 around into registration with the side 26 of the outer cube. Thus in succession the three faces of the inner cube, which meet at the lower right-hand corner of this element, are brought into registration with each of 40 the two adjacent sides of the outer cube, and similarly the three inner faces of the inner cube which meet at the upper left-hand corner are successively brought into registration with the other two lateral faces of the 45 outer cube. By indicating on the faces of the inner member such directions as "Stop", "Change", "Go", these equivalents of the ordinary traffic signals can be successively brought into registration with each of the 50 faces of the cube. Similarly, by the use of a light, such as the bulb 22, and by the use of colored lenses 30 in the inner cube colored lights can be flashed through the transparent sides of the outer casing in succession. It 55 will be understood that the arrangement and succession of signals around the two sides of the inner cube will be so correlated that as the going signals are given on two opposite sides of the outer cube to be read up and down one street, the alternate stopping signals will be given through the other two faces of the cube to be read up and down the intersecting streets, while the intermediate signals will be indicated between each 60 65 change from going to stopping.

In its simplest form my invention consists in the use of a diagonally mounted cubical element, with or without a suitable casing, the latter having openings in its four vertical faces and the inner element merely having 70 signs or words directing going, stopping and changing on its six faces, or on three in case only half the cube is used, the operation being manual where the signal is used upon a short support and operated directly by the traffic officer. Under most conditions, however, it is desired to have the signals consist of lights and to suspend the mechanism at a sufficient height above the street to permit of its being seen for a considerable distance. Under these 80 conditions colored lenses or glass may be used in the various sides of the inner cube, while the openings in the faces of the outer cube may be closed either by lenses or by glass, the signals being given from a light bulb within the inner casing, the color of which is controlled by the color of the lenses in the moving faces of the inner cube, and the inner member being operated by automatic mechanism which may take various forms for different purposes, and of which I have shown one type in Fig. 3. 85 Referring now to Fig. 3, I have already described the engagement between the gear 15 on the shaft 12 secured to the inner signaling element and the rack 16, which is formed upon a rod 35 which, at its upper end, is provided with a roll 36 operating in a cam track 37 formed on a cam 38. The latter is secured to one face of a worm gear rotatably mounted 90 in a suitable casing 40 and operated by means of a worm 42 and worm shaft 43. This latter shaft in turn carries a second worm wheel 44 which is operated by a worm 45 on the shaft 46. This shaft may be operated from any suitable source of power, such, for example, as a small electric motor which, for economy, may be operated at high speed, a great reduction in the speed being secured 95 through the double worm mechanism just described. The electric motor, which may be of any standard type and is not shown, is in constant operation and rotates the shaft 46. In this way the worm wheel 44 and shaft 43 are rotated at a greatly reduced speed, and they in turn operate the worm wheel 39 at a 100 still further reduction in speed, and in this way rotate the cam 38. As the cam is rotated the rod 35 is alternately moved up and down and is held, first in the upper position, and then in the lower position for certain periods, and is held in intermediate positions for shorter periods. The longer periods of rest cause the inner cube to be held stationary 105 with either the red or green lights or with the faces bearing the signals "Go" and "Stop" in registration with the openings in the outer casing. The shorter intermediate rests correspond either with the registration of the 110 yellow lenses, with the openings in the outer 115 casing. 120

casing, or with some equivalent signal, such as "Change" or "All Stop". It will be understood that if desired the same operation of the signal mechanism can be secured through 5 a remote control of the operation of the motor connected to the train of mechanism driving the interior cube. Should it be desired to rotate the signaling element continuously in one direction with the proper stops the above 10 mechanism would be changed to give the desired motion. The eight-sided figure would use this continuous direction to better advantage than the reversible motion shown.

In Figs. 4, 5 and 6 I have shown various 15 types and arrangements of lenses in the inner and outer casing. Thus, in Fig. 4 I have shown plain glass windows 50 in the outer casing and plain curved lenses of the various colors in the inner. In Fig. 5 I have shown plain 20 colored glass or windows 52 in the inner casing and specially formed lenses or plain glass in the outer, and in Fig. 6, plain colored glass 54 in the inner casing and plain lenses 55 in the outer.

25 In Figs. 7, 8 and 9 I have shown a modification of the inner element. In the form shown in Fig. 8 this element is provided with eight faces and is mounted about a horizontal axis extending through diagonally opposite 30 corners, the corners of the figure being cut off as before to permit of free rotation within a cubical casing. One half of the signaling elements may be used above which would signal traffic at right angles in two directions as 35 shown in Figure 10.

In Fig. 8 I have shown a plan view of this element looking at the same from a point aligned with the axis and there are thus seen to be four faces 60, 61, 62 and 63, which are 40 successively brought into registration with each vertical side wall or opening in the outer casing 65. Thus, by mounting signalling elements 66, 67, 68 and 69 of yellow, red, yellow and green glass, respectively, in these 45 four faces the going and stopping signals are given alternately with an intermediate yellow signal between each change, to give the same sequence of color signals as are ordinarily used in traffic signals today. One 50 of the two yellow signals may be of a different color to give any desired result of signaling.

The advantages of my improved signaling mechanism are its extreme simplicity, and 55 the fact that all of the desired changes and signals may be secured in a single unitary casing without the necessity for providing various banks of lights or lenses, and the further advantages that there are no exposed 60 lenses except the one through which the signal is being given to catch the glare of the sun or to confuse car drivers when looking at the signals. There is no glare from any other adjacent lenses to compete with the 65 traffic light itself, as is the case where two or

more lenses are mounted in alignment, in which case many times the glare of the sun is thrown back by the lenses which are not in operation, making it necessary to use a very strong light through the lens which is in operation in order to make the signal seen against the glow from the other two lenses. 70

It will be understood that in certain cases my improved mechanism may be used either with signal elements having six or eight faces, 75 or in certain positions even more, in which only one-half of the faces, that is, the set adjacent to one end of the shaft axis, are in operation, as for example, under conditions which are illustrated in Fig. 10. In this figure I have shown two intersecting streets 70 and 71 with signals mounted at each of the corners 72, 73, 74 and 75. A single signaling element mounted at each of these corners and provided with one-half of the inner element 80 in operation, that is, equipped with suitable transparent or translucent windows or lenses, will provide a signal facing in two directions, as indicated by the arrows. By thus mounting four semi-signaling elements at 85 such an intersection two light controls are given in each direction, that is, facing down each of the streets extending from the intersection, which will provide a very much 90 more convenient signal for car drivers than 95 present types which afford only a single light control that is visible from any one street.

Another advantage is the adaptability of the present signaling mechanism to simple hand-operated signals, to high signals mounted over or at corners of intersections and operated either remotely and manually or automatically as may be desired. 100

Other modes of applying the principle of my invention may be employed instead of 105 the one explained, change being made as regards the mechanism herein disclosed, provided the means stated by any of the following claims or the equivalent of such stated means be employed. 110

I therefore particularly point out and distinctly claim as my invention:—

1. In a signal mechanism, the combination of a supporting frame and a signaling element pivotally mounted in said supporting 115 frame about an axis extending therethrough, said element being provided with adjoining faces lying in planes at identical angles with respect to said axis, and said axis being so disposed with respect to said faces that upon 120 rotation it will bring said faces successively into substantially vertical planes.

2. In a signal mechanism, the combination of a frame and a signaling element provided with pairs of opposed parallel faces, said element being pivotally mounted about an axis 125 extending diagonally therethrough with respect to all of said faces, and said face being disposed with respect to said axis so that oscillation thereof will successively bring each 130

of said pairs of opposed faces into vertical planes.

3. In a signal mechanism, the combination of a supporting frame and a signaling element oscillatorily mounted in said frame, said element being provided with pairs of spaced parallel faces arranged in cubical relation, and said axis being disposed diagonally of the cube formed by said faces whereby oscillation of said element about said axis will successively bring into vertical planes each of said pairs of spaced parallel faces, and said faces bearing signaling indicia.

4. In a signal mechanism, the combination of a casing provided with two pairs of opposed spaced sides, the sides of said two pairs being at substantially right angles to each other, said sides being provided with openings and a signaling element oscillatorily mounted within said casing, said element being provided with pairs of spaced parallel faces and said element being oscillatorily mounted about an axis which is diagonal with respect to the sides of said outer casing and having one of the faces of each of said sets adjoining each other and making equal angles with said axis, said signaling element having signaling indicia on its various faces whereby rotation of said element will successively bring into registration with the sides of said casing, the sides of said element bearing said indicia.

5. In a signal mechanism, the combination of a supporting frame and a signaling element oscillatorily mounted in said frame, said element being provided with pairs of spaced faces arranged in cubical relation, and said axis being disposed diagonally of the cube formed by said faces whereby oscillation of said element about said axis will successively bring into vertical planes each of said pairs of spaced parallel faces, said faces bearing signaling indicia, and means for oscillating said element.

45 6. In a signal mechanism, the combination of a supporting frame and a signaling element oscillatorily mounted in said frame, said element being provided with pairs of spaced faces arranged in cubical relation, and said axis being disposed diagonally of the cube formed by said faces whereby oscillation of said element about said axis will successively bring into vertical planes each of said pairs of spaced parallel faces, said faces bearing signaling indicia, and means for automatically oscillating said element.

7. In a signal mechanism, the combination of a supporting frame and a signaling element oscillatorily mounted in said supporting frame about an axis extending diagonally therethrough, said element being provided with adjoining faces lying in planes at identical angles with respect to said axis, said axis being so disposed with respect to said faces that upon rotation it will bring said faces

successively into substantially vertical planes, and extending shields on said frame for limiting the horizontal angle through which the respective faces on said signaling element are visible.

8. In a signal mechanism, the combination of a casing, square in horizontal section and provided with translucent portions in its four sides, and a polygonally shaped element disposed within said casing and pivotally mounted upon an axis extending diagonally and horizontally through said casing, said element being provided with signaling indicia on its respective sides, and means for turning said element to bring said indicia alternately into registration with the openings in said casing.

9. In a signal mechanism, the combination of a casing in the form of a cube mounted to have four of its outer walls in vertical planes, said walls being provided with centrally disposed translucent elements therein, a signaling element consisting of a cubical member disposed within said casing, and pivotally mounted about an axis extending diagonally from one upper corner of said outer casing to an opposite lower corner and passing through one upper corner of said inner member to one opposite lower corner, an element providing a source of light disposed within said inner cube and said inner cube being provided with colored transparent elements in its respective walls, and means for rotating said inner signaling element to alternately bring the colored elements in its walls into registration with the transparent elements in the vertical walls of said outer casing.

10. In a signal mechanism, the combination of a casing in the form of a cube mounted to have four of the outer walls in vertical planes, said walls being provided with centrally disposed translucent elements therein, a signaling element consisting of a cubical member disposed within said casing, and pivotally mounted about an axis extending diagonally from one upper corner of said outer casing to an opposite lower corner and passing through one upper corner of said inner member to one opposite lower corner, an element providing a source of light disposed within said inner cube and said inner cube being provided with colored transparent elements in its respective walls, and automatically operated means for rotating said inner signaling element to alternately bring the colored elements in its walls into registration with the transparent elements in the vertical walls of said outer casing.

11. In a signal mechanism, the combination of a casing in the form of a cube mounted to have four of its outer walls in vertical planes, said walls being provided with light transmitting openings therein, a signaling element consisting of a cubical member disposed

within said casing and pivotally mounted about an axis extending diagonally from one upper corner of said outer casing to an opposite lower corner and passing through one 5 upper corner of said inner member to one opposite lower corner, a fixed tubular member concentric with said axis and extending from one of the corners of said outer casing, a source of light mounted on the inner end 10 of said tubular member, and operating means therefor disposed within said tubular member.

12. In a signal mechanism, the combination of a casing in the form of a cube mounted to 15 have four of its outer walls in vertical planes, said walls being provided with light transmitting openings therein, a signaling element consisting of a cubical member disposed within said casing and pivotally mounted about an axis extending diagonally from one 20 upper corner of said outer casing to an opposite lower corner and passing through one upper corner of said inner member to one opposite lower corner, an element providing a source of light disposed within said inner 25 cube and said inner cube being provided with colored transparent lenses in its respective walls, whereby upon rotation of said inner element the colored lenses in said inner element are successively brought into registration with the light transmitting openings in 30 said outer casing.

Signed by me, this 31 day of March, 1927.
EDWARD N. WINSLOW.
